ARVID H. NEBO, OF NEW BRITAIN, CONNECTICUT, ASSIGNOR TO THE ARROW ELECTRIC COMPANY, OF HARTFORD, CONNECTICUT, A CORPORATION OF CONNECTICUT.

CABLE GRIP.

Application filed June 8, 1923. Serial No. 644,148.

My invention relates to cable grips for pendent fittings, and particularly to fittings of the pendent socket or switch type. The object of my invention is to provide a simple and efficient cable grip which will afford efficient strain relief for the wire connections within the fitting, and prevent fraying of the cable end.

In the accompanying drawings—
10 Figs. 1, 2 and 3 are broken side elevations of pendent sockets of different types to which my invention is applied in different forms;

15 Fig. 4 is a perspective of the gripping device unassembled;

Figs. 5 and 6 are broken sections on the lines 5—5, Fig. 2, and 6—6, Fig. 3, respectively;

20 Fig. 7 is a broken side elevation of a pendent socket of still another type illustrating the application of the invention in another form thereto;

Fig. 8 is a perspective of the crown ring shown in Fig. 7; and

25 Fig. 9 is a perspective of an insulating liner for caps of the types shown in Figs. 3 and 7.

In electrical fittings of the pendent type it is desirable to relieve the binding screw 30 terminals of the suspension strain which is ordinarily taken thereby, incident to the support of the fitting at the end of the wire cable. Bad electrical conditions frequently result from defective connections between 35 the wires and the binding terminals due to this cause. The present invention provides a strain-relief device attached to the socket and gripping the wire cable in advance of its entry into the casing proper of the fitting.

40 While I have shown the invention applied to pendent sockets, its application and adaptation to electric fittings of various sorts, such as pendent switches, connectors, etc., will be obvious to those skilled in the art.

45 The socket shown in Fig. 1 is in general of common type, comprising an insulating body (not shown) housed within a casing comprising the detachable shell 15 and cap 50 16 elements telescopically interfitting and latching in the sleeved area 17 in well understood fashion. The wires 18 and 19 are, as usual, embedded in a cable 20 which enters the cap portion of the casing. The wire 55 chamber within the cap 16 is lined by a sheet

of insulation 21, to prevent contact between bared portions of the wires and the cap 16.

The strain-relief device to which my invention pertains is carried by the cap and comprises an annular base 22 from the outer margins of which extend upstanding arms 23 and 24, shaped at their free ends to form a pair of opposed wire gripping channels 25—26. Lugs 27 and 28 on the opposite sides of each channel are pierced in register 60 to receive the clamp screws 29 and 30, one of the piercings being tapped to the thread of the screw, while the other is plain, to permit the screw to pass freely therethrough. From the inner margin of the 65 ring base 22 projects the collar 31 which, when the ring 22 rests upon the annular seat 32 at the head of the cap 16, extends beyond the inner face of the seat and is thus adapted to be spread below the latter to clamp the 70 parts together.

Within the annular opening 33 afforded by the ring base 22 of the cable grip is arranged an insulating bushing 34, through which passes the cable 20 to the interior of 80 the socket casing. When the cable has been thus inserted and the wires connected to their binding terminals (not shown), the clamp screws 29 and 30 may be tightened, thus drawing together the two gripping 85 channels 25 and 26 to engage the cable 20 firmly between them. The suspension strain of the fitting is therefore now taken entirely by the cable grip and casing to which it is secured, while the binding screws are relieved from all strain.

90 In the construction shown in Fig. 2, the clamp is slightly modified in form, to accommodate it to an all-porcelain or weather-weather-proof socket. Such a socket comprises, as shown, a body portion 35 of insulation, and an insulating cap 36 centrally pierced at 37 to admit the cable to the housed wire terminals. The present cable grip is mounted on the outer face of the button 36. The base ring 38 thereof is seated directly against the outer face of the button and is clamped in position by a bridge strap 39 which overlies the base ring 38 and is secured by screws 40 passing through the 100 cap and taking into the ends of the bridge strap. The latter extends between the arms 23 and 24, which are identical with the structure first shown. The base ring 38 is sheared at opposite sides to form flats 41 110

engaged by shoulders 42 of the holding strap 39. The parts are further united and positioned by the in-turned margin 43 of the central hole 44 through the bridge strap which 5 registers with the hole 33 in the base ring 22 of the grip, and with the hole 37 in the cap portion 36 for the entry of the wire cable.

In the construction shown in Fig. 3 the 10 device is adapted to a socket having a metal casing of different type from that shown in Fig. 1. In this construction the casing comprises shell 45 and cap 46 elements which 15 sleeve but do not latch. Inasmuch as the details of this casing do not enter into the present invention, they do not need to be described further than to state that the upper insulating button 47 of the socket is secured to a crown ring 48 (Fig. 8) by screws 20 49 which take into the tapped foot pieces 50 extending from opposite sides of the ring. The cable grip device is in all essential particulars identical with that shown in Figs. 1 and 4. The ring base 22 of the cord grip 25 overlies the annular seat flange 51 of the cap 46, which in turn rests upon the crown ring 48. The neck 31 of the cord grip is spread beneath the crown ring 48 and thus rivets together the cap 46, crown ring 48, and the 30 cord grip. The button 47 of the insulating body of the socket may then be secured to this unit by the screws 49, the heads of the latter being waxed-in to permanently assemble the parts together. The ring 48 corresponds generally, it will be noted, to the 35 washer 48' beneath which the flange 31 is offset, in Fig. 1.

In the construction shown in Fig. 7, still another form of weather-proof socket is illustrated, comprising a porcelain body 52 and an independent cap button 53, which carries the same parts as those illustrated in Figs. 3 and 6. In the present form, however, the metal casing cap is substituted by 45 a finishing cap 54 which rests upon the upper face of the button 53 and it engages with the crown ring 48 and cord grip in precisely the same manner as that just described.

The cord grip device in all of the forms 50 indicated is permanently associated with the socket, and the cable cannot enter the socket for proper wiring without passing through the cord grip device. The latter presents no obstruction to the cable, but in 55 fact serves as a guide which facilitates its proper location. Its gripping action is readily effected by merely turning down the two clamping screws. The grip is readily struck from a single piece of sheet metal 60 and bent to shape, while at the same time it is rugged. Its attachment to the cap is readily and economically accomplished. In the construction shown in Figs. 3 and 7 it serves the purpose of holding the metal casing cap in position upon the insulating but-

ton of the socket—a function which must be performed by some other element if the present device is not used. It is harmonious with the general appearance of the socket, and does not detract from its appearance, 70 particularly when installed.

A further advantage derived from this construction resides in the fact that it effectively prevents ravelling of the fabric casing of the cable 20. The best and most 75 workmanlike appearance of the installation is thus assured.

Various modifications in details of construction will readily occur to those skilled in the art, without departing from what 80 I claim as my invention.

I claim—

1. A pendent fitting comprising an element apertured to afford a cable entrance, in combination with a one-piece cable grip 85 comprising a base secured to said fitting element and apertured in alignment with the cable entrance, a bushing lining said aperture, and a pair of cable-receiving jaws integral with the base and substantially axially aligned with the cable entrance of said fitting element and in extension thereof, and means for clamping said jaws upon an inserted cable.

2. As an element of a pendent fitting, a 90 cable grip comprising a pair of gripping jaws adapted to embrace a cable, means for clamping the jaws thereon, a base integral with said jaws, supporting arms extending from said base to said jaws, and flange 100 means integral with said base for permanently securing the same to an element of the fitting.

3. As an element of a pendent fitting, a 105 cable grip comprising an apertured base adapted to rest upon a fitting element, a pair of arms offset from opposite outer margins of the base, and shaped at their free ends to form opposed cable-gripping jaws, and flange means extending from the inner margins of said base for securing the same to said fitting element.

4. As an element of a pendent fitting, a 115 cable grip comprising an apertured base lying in a plane substantially at right angles to the axis of a cable passing through the aperture in the base, a pair of arms offset from the opposite outer edges of the base and shaped at their free ends to form a clamping neck substantially coaxial with the 120 aperture in the base, and flange means extending from the inner margin of the aperture in the base for securing the latter to a fitting element.

5. For permanent assembly with a pendent fitting, a cable grip device comprising a sheet metal ring having a securing flange offset from its inner margin, a pair of opposed arms offset in the opposite direction 125 from its outer margin, the free ends of said 130

arms being shaped to form clamping jaws, and means for drawing said jaws together to clamp an inserted cable.

6. For assembly with a member apertured 5 to afford a cable way, a cable grip device comprising a base ring adapted to rest upon said member concentric with said cable way, flange means offset from the inner periphery of said ring for securing the latter to said 10 member, arms extending from the outer periphery of said ring and in opposite direction from said securing flange, together with clamping jaws at the free ends of said arms, and means for drawing said jaws into 15 clamping engagement with a cable passing therethrough and through the cable way in said member.

7. A cable grip device comprising a one piece sheet metal member having a base 20 apertured to accommodate a cable passed therethrough, gripping arms offset from the outer margin of said base to engage the cable, and means offset from the inner margin of said base for attaching the same to 25 an apertured support.

8. A cable grip device comprising a one piece sheet metal member having a base apertured to accommodate a cable passed 30 therethrough, gripping arms offset from the outer margin of said base to engage the cable, and means offset from the inner mar-

gin of said base for attaching the same to an apertured support, together with an independent bushing having a flange overlying said base and lining the aperture in said 35 base.

9. An electric fitting comprising a member apertured to afford a cableway and shaped to afford a seat around said cableway, in combination with a one-piece cable 40 grip having a base resting on said seat and apertured in register with said cableway, a neck extending from the inner margin of said base into the cableway, gripping arms offset from the outer margin of said base to 45 engage an entering cable, and means for securing said cable grip to said member of the fitting.

10. An electric fitting comprising a member apertured to afford a cableway, a one-piece sheet metal cable grip having a base secured to said fitting member at the cableway and apertured to accommodate a cable passed therethrough, gripping arms extending from said base to engage a cable in advance of its entry to the fitting, and an insulating bushing lining the base of said cable grip without impeding the function of said gripping arms.

In testimony whereof I have signed my 60 name to this specification.

ARVID H. NERO.
